A. E. FAIELLA.

DIAL FOR WATCHES AND THE LIKE.

APPLICATION FILED JULY 13, 1916.

1,216,556.

Patented Feb. 20, 1917.

Inventor

Andrew E. Faiella

UNITED STATES PATENT OFFICE.

ANDREW E. FAIELLA, OF JERSEY CITY, NEW JERSEY.

DIAL FOR WATCHES AND THE LIKE.

1,216,556.

Specification of Letters Patent. Patented Feb. 20, 1917.

Application filed July 13, 1916. Serial No. 109,161.

To all whom it may concern:

Be it known that I, ANDREW E. FAIELLA, a citizen of the United States, and residing at Jersey City, in the county of Hudson and State of New Jersey, have invented certain new and useful Improvements in Dials for Watches and the like, of which the following is a specification, such as will enable those skilled in the art to which it appertains to make and use the same.

This invention relates to dials for watches and the like, and the object thereof is to provide a device of this class whereby a picture, ornament, design or the like may be formed on, or secured to, the central portion of the dial; and a further object being to provide a device of this class wherein the hour and minute hands of the watch are concealed behind the ornamental portion of the dial.

The invention is fully disclosed in the following specification, of which the accompanying drawing forms a part, in which the separate parts of my improvement are designated by suitable reference characters in each of the views, and in which:

Figure 1 is a face view of a watch indicating my improvement applied thereto;

Fig. 2 a transverse section on the line 2—2 of Fig. 1 but omitting the case of the watch; and a part of the detail works of the watch;

Fig. 3 a view similar to Fig. 2 but showing only a part of the construction and showing the same on an enlarged scale;

Fig. 4 a view similar to Fig. 2 but showing a modified form of construction and on an enlarged scale, said figure being a section on the line 4—4 of Fig. 5;

Fig. 5 a plan view of the construction shown in Fig. 4 on a reduced scale with part of the construction broken away; and,

Fig. 6 a view similar to Fig. 2 but showing only a part of the construction and showing another modification.

In Figs. 1 to 3 inclusive, I have shown one form of my improved dial construction, and in Fig. 1 I have indicated at *a* the casing of a watch having the usual stem *a*² and open face *a*³. Mounted in the casing *a* is the usual framework construction *b* in which the works of the watch are mounted, said frame consisting of a top plate *b*² and a pillar plate *b*³, and mounted between the plates *b*² and *b*³ is the usual watch mechanism only one gear and pinion *b*⁴ and *b*⁵ of which is shown, said gear and pinion being mounted on the usual arbor *c* of the watch which is mounted be-

tween the plates *b*² and *b*³, and which extends forwardly or in the direction of the face of the watch in the usual manner.

In the practice of my invention, I provide the arbor *c* with a central bore *c*² in which is mounted a pin *c*³, the inner end of which is secured in a washer *c*⁴ which is secured to the top plate *b*² by screws *c*⁵, as clearly shown in Fig. 2, and the front end of the pin *c*³ extends beyond the end of the arbor *c* and is threaded as shown at *c*⁶.

Secured to the front of the plate *b*² is a circular dial member *d*, the inner portion of which is depressed as shown at *d*², and secured to the threaded extension *c*⁶ of the pin *c*³ is a central dial member *d*³, the front face of which is provided with a sheet *d*⁴ on which is a photograph, said sheet being secured to the central dial member *d*³ in any desired manner, and between the central dial member *d*³ and the circular dial member *d* is an annular space *d*⁵, this construction being clearly shown in Figs. 1, 2 and 3.

With the construction shown in Figs. 1 to 3, I employ the usual cannon pinion *e* and hour wheel *e*² mounted thereon, and mounted on the hour wheel *e*² is the hour hand *e*³ which, in the construction shown, is bayonet in form as shown at *e*⁴ in Fig. 2, and mounted on the sleeve extension of the cannon pinion is the minute hand *e*⁵, which is bayonet in form as shown at *e*⁶.

This construction with the exception of the bayonet form of the hour and minute hands of the watch is the same as in other watches of this class and, as will be noted on a consideration of Fig. 2, the hour hand operates in the depressed portion *d*², while the minute hand extends beyond said depressed portion and to within a short distance from the perimeter of the dial member *d*. As shown in Fig. 1 the dial member *d* is provided with numerals and lines indicating the hours and minutes in connection with which the hour and minute hands operate in the usual manner. It will also be seen that the central dial member *d*³, with the picture thereon, is not defaced by the hands of the watch due to the location thereof, and yet the time may be readily determined by said hour and minute hands without any effort on the part of the owner.

In the construction shown in Figs. 4 and 5 the hour wheel *e*², or the sleeve portion thereof, is extended to the end of the arbor *c* and the sleeve portion of the cannon

pinion e , and mounted on the inner portion of the sleeve of the hour wheel is a pinion f having a sleeve portion f^2 on which is mounted the minute hand e^5 . Mounted on the sleeve portion of the hour wheel e^2 beyond the sleeve portion f^2 of the pinion f is the hour hand e^3 , and in this construction the outer end of the hour hand is bent to form a hook-shaped portion e^7 , as clearly shown in Fig. 4. The perimeter of the central dial member d^3 is provided with an hour indicating strip or portion d^8 in connection with which the hook-shaped portion e^7 and the hour hand e^3 operates, as clearly shown in Figs. 4 and 5, and the minute hand e^5 operates in connection with the dial member d , having, in the construction shown, the indications of the minutes of an hour. Between the dial member d and the central dial member d^3 is a space d^7 similar to the space d^5 in the construction shown in Fig. 2.

Mounted on the plate b^3 is a pinion g which meshes with the hour wheel e^2 , and mounted in connection with the pinion g is a gear g^2 which meshes with the pinion f on the sleeve portion of the hour wheel e^2 , and by means of this construction the minute hand may be mounted within the hour hand so as to permit the said hour hand to operate on the inner dial member d^3 as clearly shown.

In Fig. 6 of the drawing the minute hand and hour hand are mounted on the arbor c in the usual manner, or as shown in Figs. 2 and 3, but the pin c^3 is not employed and the central dial member d^3 has no connection with the arbor c but said central dial member is connected with the circular dial member d at intervals by webs or arms d^8 which are connected with the perimeter of the dial member d , and which are bent to form spaces h between the same and said dial member d , as clearly shown, and the outer end portions of the minute and hour hands operate in said spaces h , as clearly shown and the arrangement of hour and minute indicating means will be the same as in Fig. 1. The only difference between this construction and the construction shown in Figs. 1 to 3 inclusive is that the pin c^3 is omitted and the central dial member d^3 is supported by web or arm members d^8 .

It will be understood that my invention is not limited to the specific construction of the minute and hour hands, or the operating means therefor, as my improved dial construction may be employed in connection with watches, clocks and the like of various kinds and classes, as will be readily understood. The chief feature of this invention is to provide watches, clocks and the like with a central dial member which is not interrupted or defaced by the minute and hour hands of such devices. Changes in and modifications of the details of construc-

tion herein shown and described may be made, within the scope of the appended claims, without departing from the spirit of my invention or sacrificing its advantages.

Having fully described my invention what I claim as new and desire to secure by Letters Patent, is:

1. In a time piece, a central dial member having a smooth unobstructed upper surface upon which a photograph or the like may be mounted, an outer dial member spaced away from the central member and provided with numerals and lines designating minutes and hours, and a minute hand and hour hand mounted in the rear of said central member and extending through the space between the members to coöperate with the outer dial member.

2. In a time piece, a central dial member having a smooth unobstructed upper surface upon which a photograph or the like may be mounted, an outer dial member supported by the pillar plate of the time piece and spaced away from the central member, said outer member being provided with numerals and lines designating minutes and hours, and a minute hand and hour hand mounted in the rear of said central member and extending through the space between the members to coöperate with the outer dial member.

3. In a time piece, a central dial member supported by the central structure of the time piece and having a smooth unobstructed upper surface upon which a photograph or the like may be mounted, an outer dial member supported by the pillar plate of the time piece and provided with numerals and lines designating minutes and hours, said outer member being spaced away from the central member, and a minute hand and hour hand mounted in the rear of the central member and extending through the space to coöperate with the outer dial member.

4. In a device of the class described, a central dial member mounted in front of the minute and hour hands of a watch whereby said dial member may serve as an ornament supporting means, and an outer dial member provided with numerals and lines designating minutes and hours between which and said central dial member is an annular space through which said minute and hour hands operate.

5. A time piece comprising a case, plate members mounted therein, a main central tubular arbor mounted in said plate members, a pin extending through said arbor and having one end projecting beyond the same, a central dial member supported by the projecting end of said pin and having a smooth unobstructed upper surface upon which a photograph or the like may be mounted, an outer dial member supported by one of said plates and provided with numerals and lines

designating minutes and hours, said outer member being spaced away from the central member, and a minute hand and hour hand mounted upon said arbor rearwardly of the central dial member and extending through the space between the central and outer member to coöperate with the outer dial member.

In testimony that I claim the foregoing as my invention I have signed my name in ¹⁰ presence of the subscribing witnesses this 12th day of July 1916.

ANDREW E. FAIELLA.
